APPARATUS FOR MAKING RAIL JOINTS

Jonas E. Grönlund, Eskilstuna, Sweden

Application August 3, 1953, Serial No. 371,860

3 Claims. (Cl. 238—225)

The present invention pertains to apparatus for making joints between successive rail sections of railroad track and more particularly for minimizing the effect of gaps between rail sections accommodating expansion and contraction of the rails due to temperature fluctuations.

A primary object of the invention is the provision of apparatus for making such an improved joint which divides the necessary expansion gap into a plurality of smaller gaps to make possible smooth rolling passage of wheels.

Another object of the invention is to provide apparatus for such a rail joint which may be spanned between spaced ties and successfully withstand heavy loads on wheels rolling over the rails.

The invention has for a still further object the provision of such apparatus for a rail joint which, in addition, restrains the opposed rail ends against any transverse movement.

Still another object of the invention is to provide improved means for fastening such a rail joint to wooden support ties and for securing the various parts of the joint together.

Further objects and advantages of the invention will become apparent as the following description proceeds, taken in conjunction with the accompanying drawings, in which:

Figure 1 is a longitudinal elevation of a rail joint constructed in accordance with a preferred embodiment of the present invention;

Figs. 2, 3, and 4 are sectional views taken along lines 2—2, 3—3, and 4—4, respectively, in Fig. 1;

Fig. 5 is a plan view of the rail joint of the present invention showing the connected rail ends in a contracted condition such as would obtain at low temperatures;

Fig. 6 is a plan view similar to Fig. 5 showing the joined rail ends in an expanded condition which would obtain at elevated temperatures;

Fig. 7 is a perspective view of the base or supporting plate utilized in connection with the present invention;

Fig. 8 is an exploded view, in perspective, of the several parts of the present rail joint; and

Fig. 9 is a fragmentary longitudinal elevation, partially in section, corresponding to a part of Fig. 1.

Although a particular embodiment of the invention has been shown and described in some detail, there is no intention to thereby limit the invention to the details of such embodiment. On the contrary, it is intended to embrace all alterations, modifications, and equivalents falling within the scope of the invention as defined in the appended claims.

Referring now more particularly to the exemplary embodiment of the invention shown in the drawings, the apparatus there illustrated constitutes a joint between successive rails and includes a short rail section or insert 10 interposed between the opposed, spaced ends of the two rails 11 and 12. As the rails contract and expand a single, wide gap does not result, but instead, two smaller gaps, each of them one half as wide as the single

2

gap would be, occur at either end of the interposed section. This affords a much smoother rolling transition of rail car wheels across the joined ends of the rails.

The rails may be of a well known, widely used form having upper track portions 13 for rolling support of railway wheels, vertical web portions 14, and horizontal, flanged supporting bases or feet 15. The insert is of matching cross section. In order to guide the rail ends as they expand and contract relative to the intermediate section, and to provide still smoother transition of a wheel rolling over the rail ends, short horizontal recesses or grooves 16 are defined in the ends of the rails and corresponding mating projections or tongues 17 extend from either end of the insert 10 slidably into these recesses. Thus, even with the rail ends 11 and 12 fairly well contracted from the intermediate section, a complete gap between the insert and the rail ends does not result (Fig. 5).

To support the two rail ends and the insert, a base plate (Figs. 7 and 8) is provided which is adapted to underlie (Figs. 2, 3, and 4) the feet of these parts. The base plate is in the form of a relatively thin beam 18 supported at either end by spaced railroad ties 19 (Fig. 1). It includes a slot 20 defined in the underside receiving a dovetailed rib 21 secured as by welding. The reinforcing rib 21 has its greatest or deepest cross section and strength at its middle portion where bending forces are greatest. Thus, it has its maximum vertical dimension in the middle and is tapered upwardly toward the ends. Consequently, the joint need not be located directly over a tie, but in view of the strength of the reinforced base plate, may be spanned between the spaced ties. By cooperatively dovetailing the beam 18 and the rib 21, ribs of various lengths and cross sections may be readily secured to standardized beams according to the need in each particular joint as the track is laid. For example, if a joint falls between ties, a rib 21 of appropriate length may be slipped into the base plate and quickly welded thereto on the job site.

The flat upper surface of the base plate receives and supports the feet 15 of the rail ends 11 and 12 and insert 10 between two upstanding flanges 22 spaced to engage the side of the feet and positively prevent transverse movement. The rails and insert are secured in endwise slidable relation by means of suitable fasteners, such as bolts 23, extending through a series of holes 24 defined along the edges of the base plate and through registering elongated slots 25 cut into the feet. Co-operating nuts 26 engage the underside of the base plate. Positive clamping in a vertical direction with freedom for endwise sliding is accomplished preferably by a plurality of lugs 27 each carried at the upper end of one of the bolts. Each lug 27 has its inner edge drawn against the top of the feet 15 and its outer edge against the upstanding flanges 22 received in corresponding and mating grooves 28. The rail ends 11 and 12 and insert 10 are thus constrained against any vertical play, and against transverse play by side engagement with the upstanding flanges 22. Nevertheless, both the rail ends and the insert may slide in a longitudinal direction with relation to one another and the base plate. As a result, the spanned joint construction is firm in vertical and transverse direction but permits endwise sliding with temperature changes, the bolts 23 assuming different positions within the slots 25 as the rails expand and contract (Figs. 5 and 6).

It is highly important that the rail insert 10 be positively locked against vertical movement, but with freedom for lengthwise sliding movement. For example, if the hold-down bolts 23 should loosen and permit the insert 10 to rock so that one of its ends projects above the

surface of the adjacent rail, an entire train might be de-railed. If the heads of the bolts 23 for the insert 10 were in direct contact with the foot 15 thereof, longitudinal shifting of the foot might rotate the bolts sufficiently to loosen them slightly. Pounding of wheels on the insert could then completely free the bolts and let the insert rock to a position in which one of its ends projects above the adjacent rail.

The present construction eliminates these undesirable possibilities. The lugs 27, interposed between the bolt heads and the foot 15 of the insert 10, are locked against rotation by the reception of the flanges 22 in their grooves 28. Thus, the foot 15 may slide relative to the lugs 27 without in any degree tending to rotate and loosen the bolts 23.

In order to provide still further rigidity of the rail joint but at the same time leave the various parts freely slideable in an endwise direction, connecting fishplates 29 having oblong openings 30 spaced along their length are secured on either side of the webs 14 by suitable fasteners, such as bolts 31 and nuts 32, extending through registering holes 33 in the webs. Because the fishplates 29 extend to couple the webs 14 of both the rail ends 11 and 12 and the insert 10, they prevent any skewing between these parts, but the preferably oblong or elliptical openings 30 for receiving the fastening bolts 31 through the fishplates afford free relative movement of the parts in an endwise direction.

The reinforcing rib 21 is stopped short of the ends of the base plate, providing flat ends adapted to be supported by the spaced railway ties 19. As shown, particularly in Figs. 4 and 9, two openings 34 through either end of the base plate are tapped to receive correspondingly threaded fastening members. The base plate is secured to the ties by special fasteners having heads 35, upper shank portions 36 machine threaded to mate with the base plate threads, and extremities 37 formed with wood screw threads. Thus, as shown in Fig. 4, the special fasteners, carrying lugs 27 beneath their heads, are utilized both to secure the base plate to the ties, by the wood screw threads, and at the same time aid in holding the rail feet against the base plate by the machine threads. In this manner the problem of securing the rails to the base plate ends, where there is no room for cooperating nuts, such as the nuts 26 on the centrally located bolts 23, is solved. The lugs 27 carried by these special fasteners may be identical to those employed along the length of the rail joint, including a groove 28 in their underside to receive the upstanding flanges 22 in order both more positively to secure the parts and to prevent rotation of the lugs as the bolt is tightened.

It is believed that the construction, assembly, and advantages of the present invention in providing for the improved joining of two successive rails will now be apparent from the foregoing description. Through the provision of the short intermediate rail section or insert 10 slidably interposed between the joined rails, a considerable range of relative contraction and expansion of two rail ends may be accommodated without at any time producing a wide, open gap such as is often found in presently known rail joint constructions and which produces considerable jolt, as well as noise or clatter, when wheels roll over it. On the contrary, the present invention provides a sturdy rail joint construction which accommodates the expansion and contraction but yet which results in two smaller gaps, partially bridged by the cooperating, sliding projections between the insert and the rail ends, resulting in smoother and quieter transition of rolling wheels over the joined rails. Such joints may be used to advantage either when joints in side-by-side rails are staggered, as in American practice, or arranged opposite each other as in European practice.

I claim as my invention:

1. For making a joint between the ends of two rails, the combination of a rail insert matching in cross section the two rails and adapted to be interposed therebetween, a flat base plate adapted to underlie said rail ends and rail insert in endwise slideable relation, a pair of upstanding flanges along either side of the top of said base plate for preventing transverse movement of said rail ends and rail insert, a plurality of bolts inserted through said base plate and rail insert, a corresponding plurality of lugs interposed between said bolts and the rail insert, said lugs having grooves receiving said flanges as the bolts are tightened to thereby prevent rotation and loosening of the bolts by endwise shifting of the rail insert, a lengthwise groove being defined in the underside of said base plate, and a reinforcing rib keyed into said groove and extending along the middle portion of said base plate to leave two flat surfaces on its underside for support, said rib preventing downward bowing due to weight on said insert when said base plate is supported at either end.
2. For making a joint in railroad rails, the combination of a base plate having end portions adapted to be supported by spaced railroad ties and having on its underside a longitudinal dovetail groove, a reinforcing rib adapted for captive insertion in said dovetail groove and having its greatest cross section in the middle of the base plate and tapering in cross section toward the two end portions, a rail insert matching in cross section the two rails to be joined, said two rails with said insert interposed therebetween being supported at the feet thereof by the top of said base plate, and means for fastening the rail ends and said insert to the base plate in relative endwise slideable relation.
3. For making a joint between the opposed ends of two rails having horizontal flanged feet, the combination comprising a rail insert matching the rails in cross section, a base plate having a flat upper surface and upstanding flanges along its longer edges for receiving the feet of the rail ends in opposed spaced relation with said insert interposed therebetween, the rail ends having horizontally extending recesses in the upper surfaces thereof, cooperating tongues extending lengthwise from either end of said insert to slidably engage the rail ends in said recesses, the feet of said rail ends and insert having longitudinally spaced elongated slots and the base plate having registering holes, a plurality of headed bolts inserted through corresponding ones of said slots and holes, a plurality of lugs each interposed between the head of one of said bolts and the underlying foot, said lugs having grooves receiving said flanges as the bolts are tightened, the lugs holding the rail ends and insert while permitting endwise shifting thereof without loosening of said bolts and the upstanding flanges preventing transverse movement of the rail ends and insert relative to the base plate, and means including a fishplate connecting the rail ends and the insert for preventing relative skewing, said last named means further including registering oblong holes defined through said rail ends and insert and fasteners therethrough for permitting relative endwise movement, contraction of the rails resulting in a relatively small gap between each rail end and said insert providing smooth passage of wheels over the joined rails.
